UNITED STATES PATENT OFFICE.

CHARLES CHRISTIAN WAIS, OF OAKLEY, OHIO.

MACHINE FOR CUTTING OUT CIRCULAR OR ELLIPTICAL FORMS.

No. 873,395.

Specification of Letters Patent.

Patented Dec. 10, 1907.

Application filed January 10, 1906. Serial No. 295,362.

To all whom it may concern:

Be it known that I, CHARLES CHRISTIAN WAIS, a citizen of the United States of America, and resident of Madison and Gilmore 5 avenues, Oakley, county of Hamilton and State of Ohio, (post-office address Plum and Pearl streets, in the city of Cincinnati, county of Hamilton, and State of Ohio,) have invented an Improvement in Machines for Cutting Out Circular or Elliptical Forms; and I do hereby declare the following to be a full and exact description thereof, reference being had to the accompanying drawings, making part of this specification.

15 My invention relates to machines for cutting out circular or elliptical forms, and it has for its object the improvement in the construction of such devices whereby they are simplified and rendered more efficient in 20 action.

The novelty of my invention consists in the combination and sub-combination of the parts as will be hereinafter set forth and specifically pointed out in the claims.

25 Figure 1 is a side elevation of my boring, turning and facing machine for circular elliptical and other irregular forms. Fig. 2 is a front elevation. Fig. 3 is a section on line 3—3 of Fig. 2. Fig. 4 is a front view of the tool carrying head. Fig. 5 is a section on line 5—5 of Fig. 2. Fig. 6 is a section on line 6—6 of Fig. 1. Fig. 7 is a bottom view of the tool holder. Fig. 8 is a diagrammatic sketch showing how the spindle works when 35 the back gear is out. Fig. 9 is a diagrammatic sketch showing the path of the tool when the back gear is out, and cam is not in action. Fig. 10 is a diagrammatic sketch showing back gear in, and power transmitted 40 from back gear to gear on spindle by one idler, the back gear and gear on spindle being the same diameter. Figs. 11, 12 and 13 are examples of paths the tool will take under varying ratios between the radius of tool 45 from spindle center and throw of eccentric, with Fig. 10 gearing. Fig. 14 is a diagrammatic sketch showing back gear in, and power transmitted from back gear to gear on spindle by one idler, the back gear being half the 50 diameter of the gear on spindle. Fig. 15 shows path the tool will take with a certain ratio existing between the radius of tool from spindle center and throw of eccentric with Fig. 14 gearing. Other paths can be 55 traced with Fig. 14 gearing by changing the ratio between radius of tool from spindle cen-

ter and throw of eccentric. Fig. 16 is a diagrammatic sketch showing back gear in, and power transmitted from back gear to gear on spindle by two idlers, the back gear being 60 half the diameter of the gear on spindle. Fig. 17 shows path the tool will take with a certain ratio existing between the radius of tool from spindle center and throw of eccentric with Fig. 16 gearing. Other paths can 65 be traced with Fig. 16 gearing by changing the ratio between radius of tool from spindle center and throw of eccentric. Fig. 18 is a diagrammatic sketch showing back gear in, and power transmitted from back gear to 70 gear on spindle by one idler, the back gear being one-third the diameter of the gear on spindle. Fig. 19 shows path the tool will take with a certain ratio existing between the radius of tool from spindle center and 75 throw of eccentric with Fig. 18 gearing. Other paths can be traced with Fig. 18 gearing by changing the ratio between radius of tool from spindle center and throw of eccentric. Fig. 20 is a partial section of cam E, 80 showing how gear C, is clamped to cam E.

Similar letters indicate like parts in the several drawings.

A represents the frame of my boring, turning and facing machine for circular elliptical 85 and other irregular forms.

A² is the base.

A³ is the table.

A⁴ and A⁵ is a tight and loose pulley.

A⁶ and A⁷ are cone pulleys for changing 90 speeds.

A⁸ is a shaft for transmitting power to the bevel gearing A⁹, A¹⁰, A¹¹.

A¹², A¹³, A¹⁴, A¹⁵ are spur gears for communicating power from bevel gears to main 95 spindle A¹⁶.

A¹⁷ is a cone pulley on top of spindle A¹⁶ for transmitting power to cone pulley A¹⁸. Cone pulley A¹⁸ transmits power through shaft A¹⁹ and gears A²⁰, A²¹, and shaft A²² to 100 feed mechanism A²³. The main spindle A¹⁶ has near its top a gear A²⁴ which transmits power to the vertical shaft B through gears B' and B². The vertical shaft B is suitably supported in bearings B³ and B⁴. At the 105 lower end of the shaft B is a gear B⁵ which meshes with gear C. Gear C turns loosely on the sleeve C². The gear C can be clamped to the cam E when the cam has been set for any desired throw. The throw 110 of the cam E, is changed by loosening the nuts on the bolt shown in Fig. 20, setting the

cam to any desired position and tightening the nuts again. The cam E has a slot E² which permits the throw of the cam to be changed. The cam strap E³ is attached to the tool holder G so that when the cam E turns the tool holder G will slide back and forth according to the throw of the cam as well as turning around with the spindle A¹⁶. The tool holder G slides back and forth on the 10 slide F. Attached to the sleeve C² is a rack H, which meshes with a pinion H²; the pinion H² is pivoted to the arm I, which projects from the front of the frame A. By turning the pinion the sleeves C² can be raised or 15 lowered as may be desired.

The operation of my machine is as follows. Power is transmitted in a suitable manner to the spindle A¹⁶. From spindle A¹⁶ power is transmitted to the upright spindle B, through 20 the gear B', causing the spindle B, to revolve in the same direction as spindle A¹⁶. The lower end of the shaft or spindle B, has a gear B⁵ which meshes with gear C, the gear C turns loosely on the sleeve C² but the shaft B 25 being geared to the gear C, direct it causes the gear C to revolve in the opposite direction from which the shaft B, revolves. The spindle A¹⁶ revolves the same as shaft B, on the spindle A¹⁶ the tool holder is attached. 30 The cam E, when set at the throw desired will be clamped to the gear C, when the cam will revolve in the opposite direction. When operated in this manner an ellipse can be cut out of a plate by the tool, when forced 35 down on to the work by means of the rack and pinion H, H².

With my machine it is possible to have the cutting tool revolve in the same direction

that the cam does, or it can be geared to revolve in the opposite direction from the cam. 40

Although my machine is well adapted for cutting out irregular forms from plate metal, it is also suited for turning an indefinite number of forms for ornamental figures on watch cases, silver ware, and similar articles. 45

Having described my invention what I claim is:

1. In a machine of the class described, the combination of a rotatable shaft, a tool holder supported by and rotating with said shaft, a cam adapted to impart lateral motion to the tool holder, and mechanism driven by said shaft to rotate said cam, all substantially as described.

2. In a machine of the class described, the combination of a rotatable shaft, a tool holder supported by and rotating with said shaft, a cam adapted to impart lateral motion to the tool holder, means for changing the throw of the cam, and mechanism driven by said shaft to rotate said cam, all substantially as described.

3. In a machine of the class described, the combination of a rotatable shaft, a tool holder supported by and rotating with said shaft, means for adjusting the tool, a cam adapted to impart lateral motion to the tool holder, means for changing the throw of the cam, and mechanism driven by said shaft to rotate said cam, all substantially as de- 70 scribed.

CHRIST. WAIS.
